CLAIM

I claim the ornamental design for a chair, as shown and described.

DESCRIPTION

FIG. 1 is a top perspective view of a chair, showing our new design;

FIG. 2 is a front view of the chair thereof;

FIG. 3 is a rear view of the chair thereof;

FIG. 4 is a right-side view of the chair of FIG. 1, the left-side view is a mirror image of the right-side view of FIG. 4;

FIG. 5 is a top view of the chair thereof;

FIG. 6 is a bottom view of the chair thereof; and,

FIG. 7 is a cross-sectional view of the chair taken along lines VII-VII of FIG. 3.

The dashed lines are for purposes of illustrating environmental structure and form no part of the claimed design.
